UNITED STATES PATENT OFFICE.

JOHN A. LE CATO, OF NEW YORK, N. Y., ASSIGNOR TO STANDARD PNEUMATIC ACTION CO., OF NEW YORK, N. Y., A CORPORATION OF NEW YORK.

TRACKING DEVICE.

1,260,004.

Specification of Letters Patent. Patented Mar. 19, 1918.

Application filed August 20, 1917. Serial No. 187,144.

To all whom it may concern:

Be it known that I, JOHN A. LE CATO, a citizen of the United States, residing at New York, in the county of New York and State 5 of New York, have invented a new and useful Tracking Device, of which the following is a specification.

This invention relates to a tracking device for automatic musical instruments.

10 Provision has been heretofore made for adjusting the tracker bar relatively to the note sheet to correct inaccurate alinement of the note openings, and also for transposing the musical selection to a different key. 15 Pneumatic sheet adjusting mechanism, and pneumatic expression devices have also been heretofore used, both controlled from supplementary openings in the tracker bar.

To the best of my knowledge and belief, 20 however, no effective construction has been heretofore devised which permitted these several devices to be used together in the same instrument. The movable tracker, as commonly constructed, precluded the use of 25 fixed guide and expression openings.

Accordingly, it is the general object of 30 my invention to provide a construction by means of which relative adjustment may be secured between the guide and expression openings of the tracker bar and the playing openings therein. In the preferred construction, the guide and expression openings are fixed in position and rigidly spaced from each other, while the playing openings are adjustable transversely of the note 35 sheet.

With this general object in view, my invention relates more specifically to certain arrangements and combinations of parts 40 which will be hereinafter described and more particularly pointed out in the appended claims.

A preferred form of my invention is shown in the drawings, in which—

45 Figure 1 is a front elevation of my improved tracker bar, together with a portion of the spool supporting frame;

Fig. 2 is a horizontal sectional view taken substantially along the line 2—2 in Fig. 1;

50 Fig. 3 is a rear elevation of a portion of the tracker bar, looking in the direction of arrow 3 in Fig. 2;

Fig. 4 is a transverse sectional elevation taken along the line 4—4 in Fig. 1, and

55 Fig. 5 is a detailed perspective view of

one of the fixed tracker bar sections containing guide and expression control openings.

Referring to the drawings I have shown a movable tracker bar 10 supported at its opposite ends by frame members 11 and 12. 60 The rear edges of the bar are grooved to receive the edges of plates 13 and 14, which is a usual construction. The note sheet is indicated in broken lines at N (Fig. 1).

The tracker bar 10 is provided on its rear 65 side with a longitudinally extending rectangular groove 15 (Fig. 4) and the bar is also provided with slots 16 and 17 extending through to the face of the bar.

Short tracker bar sections 18 (Fig. 5) and 70 19 are rigidly secured to the frame members 11 and 12 by screws 20, and these tracker bar sections are provided with blocks 21 extending through the slots 16 and 17 and having their front faces flush with the front surface 75 of the tracker bar 10.

One or more guide openings 22 and expression openings 23 are provided in the blocks 21, said openings extending through the bars 18 and 19 and the blocks 21 at one 80 or both edges of the note sheet. Flexible tubes 24 are connected in the usual way to the openings 22 and 23, and also to the regular playing openings 25 in the bar 10.

The sheet adjusting and expression controlling mechanisms to which the flexible tubes 24 from the openings 22 and 23 are connected are devices well-known in the art and may be of any usual construction. For this reason these devices are not shown in 85 the drawings, but reference is made to the patent to Danquard, No. 1,187,975, issued June 20, 1916, as disclosing one suitable form of sheet adjusting mechanism, and to the patent to Crinnen, No. 977,072, issued 90 November 29, 1910, as showing a suitable form of expression controlling mechanism.

The bar 10 is slidably secured in position on the frame members 11 and 12 in any convenient manner, as by straps 26 and screws 100 27 (Fig. 1).

I have found it desirable to rigidly connect the fixed tracker bar sections 18 and 19 by a U-shaped link 28 (Fig. 3) which may be secured by screws 29 to the bar sections 105 18 and 19.

A pin 30 is secured in the back side of the bar 10 in one end thereof, this pin being received in a slot 31 formed in one arm of a bell-crank 32 pivoted at 33 to a bracket 110

mounted on the frame member 11. The second arm of the bell-crank extends through a slot in the frame member 11, and is provided at its inner end with a handle 34 by 5 which the bar 10 may be adjusted transversely of the note sheet. Graduations 35 (Fig. 1) provide means by which the adjustment may be more accurately made.

With this construction it will be seen that 10 the guide openings 22 and the expression openings 23 may be fixed in position, thus guiding the note sheet in a fixed path and controlling the expression regardless of the adjustment of the tracker bar 10. At the 15 same time, the bar 10 may be adjusted transversely by the handle 34 so that the selection may be played in any desired key or the alignment of the note sheet openings may be corrected. By this combination I am thus 20 enabled to secure all the advantages of the well known tracking and expression devices while at the same time I avail myself of the transposing features of the movable tracker bar.

Having thus described my invention it will 25 be evident that changes and modifications can be made therein by those skilled in the art, without departing from the spirit and scope of my invention as set forth in the

claims, and I do not wish to be otherwise 30 limited to the details herein disclosed, but what I claim is:—

1. In an automatic musical instrument, a spool supporting frame, a main tracker bar grooved longitudinally and slotted near its 35 opposite ends, said tracker bar being slideable transversely of said frame, bar sections fixed to said frame and positioned in said groove, blocks fixed to said bars, extending into said slots, and having guide openings 40 therein from which sheet adjusting mechanism may be controlled, and means to adjust said main tracker bar.

2. In an automatic musical instrument, a spool supporting frame, tracker bar sections 45 fixed thereto and rigidly connected together, a tracker bar grooved and slotted to permit movement relative to said fixed sections, means to retain said bar in operative position in said frame, and manual means to adjust said bar longitudinally, said fixed bar sections having openings therein for the control of sheet adjusting mechanism and additional openings for the control of expression mechanism.

In testimony whereof I have hereunto affixed my signature.

JOHN A. LE CATO.
